PRESSURE ROLLER APPLICATOR

William Niemi, 28122 Deep Creek,
Saugus, Calif. 91350

Filed Mar. 9, 1973, Ser. No. 339,603

Term of patent 14 years

Int. Cl. D8—05

U.S. Cl. D8—51

FIG. 1

FIG. 2

FIG. 3

FIG. 4

FIG. 1 is a perspective view showing my new design for a pressure roller applicator;

FIG. 2 is a side elevational view thereof;

FIG. 3 is a side elevational view opposite to the side shown in FIG. 2; and

FIG. 4 is an end elevational view thereof.

I claim:

The ornamental design for a pressure roller applicator, substantially as shown and described.
